(57) **CLAIM**

The ornamental design for a root irrigation apparatus, as shown and described.

DESCRIPTION

FIG. 1 is a perspective view of a root irrigation apparatus; FIG. 2 is a right elevation view of the root irrigation apparatus;

FIG. 3 is a rear elevation view of the root irrigation apparatus;

FIG. 4 is a left elevation view of the root irrigation apparatus;

FIG. 5 is a front elevation view of the root irrigation apparatus;

FIG. 6 is a top plan view of the root irrigation apparatus;

FIG. 7 is a bottom plan view of the root irrigation apparatus;

FIG. 8 is a perspective view of another embodiment of the root irrigation apparatus with indeterminate length;

FIG. 9 is a right elevation view of another embodiment of the root irrigation apparatus with indeterminate length;

FIG. 10 is a rear elevation view of another embodiment of the root irrigation apparatus with indeterminate length;

FIG. 11 is a left elevation view of another embodiment of the root irrigation apparatus with indeterminate length;

FIG. 12 is a front elevation view of another embodiment of the root irrigation apparatus with indeterminate length;

FIG. 13 is a top plan view of another embodiment of the root irrigation apparatus with indeterminate length;

FIG. 14 is a bottom plan view of another embodiment of the root irrigation apparatus with indeterminate length;

FIG. 15 is a perspective view of the root irrigation apparatus retracted;

FIG. 16 is a right elevation view of the root irrigation apparatus retracted;

FIG. 17 is a rear elevation view of the root irrigation apparatus retracted;

FIG. 18 is a left elevation view of the root irrigation apparatus retracted;

FIG. 19 is a front elevation view of the root irrigation apparatus retracted;

FIG. 20 is a top plan view of the root irrigation apparatus retracted;

FIG. 21 is a bottom plan view of the root irrigation apparatus retracted;

FIG. 22 is a perspective view of another embodiment of the root irrigation apparatus retracted with indeterminate length;

FIG. 23 is a right elevation view of another embodiment of the root irrigation apparatus retracted with indeterminate length;

(Continued)

FIG. 24 is a rear elevation view of another embodiment of the root irrigation apparatus retracted with indeterminate length;

FIG. 25 is a left elevation view of another embodiment of the root irrigation apparatus retracted with indeterminate length; FIG. 26 is a front elevation view of another embodiment of the root irrigation apparatus retracted with indeterminate length;

FIG. 27 is a top plan view of another embodiment of the root irrigation apparatus retracted with indeterminate length; and, FIG. 28 is a bottom plan view of another embodiment of the root irrigation apparatus retracted with indeterminate length.

The phantom lines of FIGS. 1-28 are included for the purpose of illustration and forms no part of the claimed design.
